UNITED STATES PATENT OFFICE

JOSEPH COURY, OF PARIS, FRANCE, ASSIGNOR TO THE SOCIETY MANUFACTURE DE BONNETERIE DE L'ARGONNE, OF VIENNE LE CHATEAU, FRANCE

* METHOD FOR PRODUCING KNITTED HOSE, STOCKINGS, AND THE LIKE

Application filed September 26, 1928, Serial No. 308,892, and in France March 13, 1928.

The present invention relates to improved methods for producing knitted hose, stockings and the like, and to the article so produced.

5 One of the objects of the invention is to provide a simplified method for forming a stocking having a seamless leg portion and a formed foot portion resembling very closely what is termed in the French trade as 10 "diminué" i. e. as having a form which fits the foot and leg.

Other objects will appear in the course of the detailed description now to be given with reference to the accompanying drawings, in 15 which:—

Fig. 1 represents, in perspective, a stocking at the first stage of the manufacturing operation;

Fig. 2 is a perspective, showing a second 20 stage; and

Fig. 3 a perspective of the finished article.

Fig. 4 represents one stage in the manufacturing operation.

The complete stocking is formed in the 25 following series of operations.

The leg portion 1 and reenforced heel 2 are first formed in a circular machine in the same manner as stockings of the so-called "standard" circular type, the knitting operation being extended so as to provide a short instep portion 3. That is, the leg 1 is knit as a tubular portion until the heel is reached. The needles on one side of the machine are then thrown out of action, and a semicylindrical heel portion 2', 3' is then knit, while 35 the instep portion is not knit. The semicylindrical portion is then drawn down and on its edges 9 and on the edge 3a of the unknit tubular portion a short cylindrical portion 3,

40 8a is knit. The parts 2', 3' thus form loops 5, as shown in Fig. 1. The stocking is then taken out of the circular machine and slit longitudinally along the wales at two lines 4 at the lateral extremities of the reinforced portion substantially as shown in the drawing, up to openings 5 of the "pocket" or curved portion of the heel. The rear part of 45 the stocking and the heel are then slit along a line 6 for a distance of approximately 20

50 centimeters corresponding to the heel plus the

ankle so that segments 2' and 3' on each side of line 6 are symmetrical. If desired, a tracing of line 6 may be formed in the stocking during its formation by one of the needles of the circular machine in a manner obvious to those skilled in the art. The stocking, with slits 4 and 6 formed therein, is then mounted in any standard type of flat rectilinear machine so that the rear edge 3a of portion 3 and selvage edges 8 are supported in the same straight line (Fig. 4) on a line of needles. The instep portion 3 and preferably the portions 8a of the heel portion are unravelled and discarded. The first course of the foot is then drawn through the loops of the selvage 8 of the semicylindrical portion and of the edge 3a of the tubular portion. The developed foot portion tapering to a point, is then knit in a manner which will be obvious to those skilled in the art. To complete the 70 stocking it suffices only (1) to trim the toe and heel, (2) to then turn the knitted foot portion under so that the free edges lie along the center-line of the sole and (3) to stitch the sole along line 7 and the heel and ankle along lines 6 and 4. The finished stocking instead of having the "non-fitting" section of the article produced on a circular machine, fits the foot and leg in the same manner as the expensive type of formed stocking made 75 entirely in a rectilinear machine. The stitching operation along line 6 may be continued upward along the rear seam-line of the leg to remove any suspicion of the articles having been formed in a circular machine.

80 From the foregoing it will be seen that instead of producing a "formed" stocking completely in a flat rectilinear machine as has hitherto been necessary, the greater part thereof i. e. the entire leg and heel may be 85 knit in a circular machine, thus effecting a very considerable saving in the cost of manufacture without any sacrifice in the attractiveness or form of the finished article.

90 What I claim is:—

95 The improvement in the art of knitting fashioned hosiery, which consists in first knitting the leg as a continuous tubular web, then knitting a semicylindrical heel portion without knitting an instep portion, then knit- 100

ting a short cylindrical portion whereby said semicylindrical portion forms a loop, cutting said short cylindrical portion on each side along the wales to open said loop slitting the stocking along the back of the heel portion then discarding the instep part of said short cylindrical portion and knitting the foot as a flat web, the first course of which is drawn through the selvage loops of the semicylindrical portion and the last loops of that portion of the tubular web portion to which the semicylindrical portion is not attached.

In testimony whereof I have hereunto set
15 my hand.

JOSEPH COURY.
